CLAIM

The ornamental design for a phone cover as shown and described.

DESCRIPTION

FIG. 1 is a perspective view of a phone cover showing my new design;

FIG. 2 is another perspective view thereof;

FIG. 3 is a perspective view of the phone cover where the phone cover is in a configuration of use;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof; and,

FIG. 10 is an enlarged view of portion 10 shown in FIG. 2. The dash-dash broken lines in the drawings depict portions of the phone cover that form no part of the claimed design. The dot-dash broken lines represent a boundary of the enlarged portion and form no part of the claimed design.

1 Claim, 10 Drawing Sheets
